The ornamental design for a perforated hollow spike to facilitate the watering of plants, as shown.

DESCRIPTION

FIG. 1 is a top plan view of a perforated hollow spike to facilitate the watering of plants in accordance with my invention;

FIG. 2 is a front elevational view thereof;

FIG. 3 is a right-side elevational view thereof;

FIG. 4 is a left-side elevational view thereof;

FIG. 5 is a rear elevational view thereof;

FIG. 6 is a bottom view thereof;

FIG. 7 is a cross-sectional view along lines 7—7;

FIG. 8 is a first perspective view thereof; and,

FIG. 9 is a second perspective view thereof.

The structure indicated in the drawing figures by broken lines is not part of the design sought to be patented in this application.
